(57) **CLAIM**

The ornamental design for circuit breaker and components therefor, as shown and described.

DESCRIPTION

FIG. 1 is a perspective view of a first embodiment of a circuit breaker and components therefor showing our new design; FIG. 2 is a front view thereof;

FIG. 3 is a top view thereof;

FIG. 4 is a rear view thereof;

FIG. 5 is a left view thereof;

FIG. 6 is a right view thereof;

FIG. 7 is a perspective view of a second embodiment of a circuit breaker and components therefor showing our new design;

FIG. 8 is a front view thereof;

FIG. 9 is a top view thereof;

FIG. 10 is a rear view thereof;

FIG. 11 is a left view thereof;

FIG. 12 is a right view thereof;
FIG. 13 is a perspective view of a third embodiment of a circuit breaker and components therefor showing our new design;
FIG. 14 is a front view thereof;
FIG. 15 is a top view thereof;
FIG. 16 is a rear view thereof;
FIG. 17 is a left view thereof;
FIG. 18 is a right view thereof;
FIG. 19 is a perspective view of a fourth embodiment of a circuit breaker and components therefor showing our new design;
FIG. 20 is a front view thereof;
FIG. 21 is a top view thereof;
FIG. 22 is a rear view thereof;
FIG. 23 is a left view thereof;
FIG. 24 is a right view thereof;
FIG. 25 is a perspective view of a fifth embodiment of a circuit breaker and components therefor showing our new design;

FIG. 26 is a front view thereof;
FIG. 27 is a top view thereof;
FIG. 28 is a rear view thereof;
FIG. 29 is a left view thereof;
FIG. 30 is a right view thereof;
FIG. 31 is a perspective view of a sixth embodiment of a circuit breaker and components therefor showing our new design;
FIG. 32 is a front view thereof;
FIG. 33 is a top view thereof;
FIG. 34 is a rear view thereof;
FIG. 35 is a left view thereof; and,
FIG. 36 is a right view thereof.

The features and portions of the circuit breaker and components therefore shown in broken lines form no part of the claimed design.
